UNITED STATES PATENT OFFICE

2,445,403

PORTABLE DRIER

Phillip Mayerman, Yonkers, N. Y.

Application July 1, 1947, Serial No. 758,422

2 Claims. (Cl. 34—163)

1

This invention relates to novel and useful improvements in clothes drying devices of the electrically heated, forced draft, collapsible type.

An object of this invention is to provide a housing having collapsible clothes retaining means located therein, said means being selectively entirely received in said housing and adjustable to a position projecting therefrom.

Another object of this invention is to provide a case in said housing means for receiving heating means therein and for receiving means for impelling air over said heating means and through the clothes retained on said clothes retaining means.

Another object of this invention is to provide timing means associated with said air impelling means.

A further object of this invention is to provide a cover means for said clothes retaining means whereby air may be restricted within certain predetermined travel.

A further object of this invention is to provide means for selectively retaining said clothes retaining means in predetermined, adjusted position.

Another object of the present invention is to provide means for engaging and retaining said cover means in certain predetermined positions.

Another object of this invention is to provide a portable device of the character described which is both inexpensive, efficient in its intended operation and which lends itself well to commercial manufacture.

Ancillary objects and features of novelty shall become apparent to those skilled in the art, in following the description of the preferred form of the present invention, illustrated in the accompanying drawings, wherein:

Figure 1 is a perspective view of the preferred form of the present invention, parts being broken away in section to illustrate details of construction;

Figure 2 is an elevational plan view of the preferred form of the present invention, showing the same in a collapsed position and also showing portions broken away in section to further illustrate details of construction;

Figure 3 is a transverse sectional view of the preferred form of the present invention, illustrating particularly the arrangement of clothes retaining means and the air impelling means;

Figure 4 is a sectional detail of construction taken substantially on the line 4—4 of Figure 1 and in the direction of the arrows;

Figure 5 is a further detail of construction

2

taken substantially on the line 5—5 of Figure 3 and in the direction of the arrows;

Figure 6 is a sectional detail of construction taken on the line 6—6 of Figure 4 and in the direction of the arrows;

Figure 7 is a perspective view illustrating a swivel joint used in conjunction with the present invention;

Figure 8 is a sectional view of the clamp means used in conjunction and forming part of the present invention and taken substantially on the line 8—8 of Figure 1 and taken in the direction of the arrows, and;

Figure 9 is a sectional detail of construction taken on the line 9—9 of Figure 3 and in the direction of the arrows.

Referring now in detail to the illustrated preferred embodiment of the present invention, like reference characters are used throughout to indicate similar elements thereof.

A box-like housing 10 having a cover 12 hingedly secured thereto is provided as a recipient of various components forming the present invention. Conventional hinges 14 are utilized in holding the lid 12 to the said housing 10 and suitable securing means are utilized in securing the hinges in the usual operative manner. It is noted at this point that the preferred material of construction is metallic, however, it is within the purview of the present invention to utilize other materials such as plastic and the like.

A base frame 16 is received in the bottom 18 of the said housing 10 and may be simply rested therein or rigidly secured, if so desired. A frame member, collapsible in nature and generally indicated at 20 is used in association with the base frame 16. The said collapsible apparatus 20 is composed of a plurality of substantially rectangular frame members 22 which are pivotally secured together substantially intermediate the shorter legs thereof. The said shorter legs 24 and 26 may be seen in Figure 5 wherein this hinged connection is disclosed. A brace member 28 extends across selected shorter legs, penetrating the inside legs of the frame which happens to be slightly smaller than the associated frame 22 and said cross member 28 terminates within the shorter legs of the said outer frame 22. A washer 30 serving the purpose of a spacer may be interposed between the said shorter legs 24 and 26 respectively as shown in Figure 5. Then, the terminal portion of the said shorter legs are hingedly mounted in a selected manner as shown particularly well in Figure 4.

As seen in Figure 7, the corner segments of the frame 22 may have apertures in a selected base portion 38. Legs 24 are provided with reduced right angular extensions rotatively received in the apertures and set screw means 60 engageable with the said portion 38 and extensions. This specific structure will be set forth as the description proceeds.

A pair of clamp members 42 and 44 respectively are rigidly secured to the said base frame member 16 by some suitable means such as the rivet means 46 disclosed in Figure 9. A pair of hooks 48 is secured to each of the said clamp members for the purpose of receiving the lowermost longer side member 50 of a selected frame 22. It can be readily appreciated from an inspection of Figure 1 that the said collapsible frame apparatus 20 may be adjusted selectively in vertical positions by utility of selected hooks 48. Also, as is seen in Figure 3 the said frame apparatus 22 may be entirely received within the receptacle or housing 10.

Reference is now made to Figure 4, wherein there is disclosed a joint utilized throughout certain portions of the collapsible apparatus 20. The terminal portions of a selected frame 22 are provided with reduced shanks 54 which are received in the bore of an adjacent longer leg 34. Thrust bearings 56 may be interposed between a suitable shoulder 58 on the said reduced portion and terminal portion of the said longer leg 34. Set screw means 60 is employed in suitable apertures preferably having countersunk cooperating apertures, for the purpose of providing friction between moving elements. As will be noted from an inspection of Figure 6 there is an annular groove 62 cooperating with the said suitable recess. This annular groove 62 is provided about the periphery of the said reduced portion 54 and received in the terminal portion of the said set screw means 60 therein.

A case 66 is provided on the base 18 of the said housing 10 and a detachable foraminous lid 68 is provided thereon. Heating means, preferably electrically operated heated elements 70 are stretched across the said case 66 and are retained there by suitable brackets 69.

Means for impelling air over said and through said heating means is provided. This last mentioned means is preferably electric motor means 73 having fan blades 74 driven thereby. It will be noted that any number of motor and blade assemblies may be employed in accordance with the dictates of sound engineering practice. A conventional timing device, generally indicated at 76 is provided within said case 66 and is associated with the said motor means 73 through the utility of an electrical conduit 78. This timing means 76 is purely conventional and has associated therewith a usual switch 80.

As is seen in Figure 1 a cover means 82 is employed over the said collapsible clothes retaining means for the purpose of restricting the air to predetermined, prescribed travel. In the collapsed position, as is seen in Figure 3, the said cover means is retained on the upper portion of the said collapsible clothes retaining apparatus 20, through the utility of the said clamp device 84, which is seen in Figure 8. This clamping device 84 consists of a plurality of hooks and a bearing

member 86 integral therewith. This bearing member 86 has a slot 88 therein and a lug, received in the selected shorter legs 24 and 26, which is slidably received in said slot. This lug 90 may be a simple pin having ribs at one end thereof and received in a suitable threaded aperture. Of course, the said clamp 84 may be rotated about the shorter legs 24 and 26, and the rotation is limited by contact of the said lug 90 against the extremities of the slot 88.

While there has been described and illustrated but a single preferred embodiment of the present invention, it is apparent to those skilled in the art, that various changes including omissions, additions and rearrangement of elements may be made herein without departing from the spirit of the invention. Accordingly, limitation is sought only in accordance with the scope of the following claims.

Having described the invention, what is claimed as new is:

1. A portable dryer comprising a rectangular housing having a base and removable cover for the top thereof, a drying frame formed of a plurality of intersecting articulated rods interconnecting a plurality of horizontal rods adapted to assume different levels as said frame is adjusted between its maximum raised level above the base of said housing and its minimum level when the same is in collapsed position fully within the confines of said housing and cover, abutments mounted on one side of the base of said housing and engaging one of the lowermost horizontal rods for adjusting the lateral distension of said drying rack and consequently the levels of said horizontal rods, a heating chamber mounted on the opposite side of the base of said housing and underlying the rack in all positions thereof, said heating chamber containing electrical heating means therein and a circulating fan for directing heated air upwardly between the lateral boundaries of said drying frame.

2. A portable dryer as set forth in claim 1 embodying a unitary flexible covering overlying the top of the drying frame and extending downwardly along all sides thereof in its extended position.

PHILLIP MAYERMAN.
